MIXING DEVICE FOR OIL BURNERS

Waid C. Pait, Bladenboro, N. C.

Application November 18, 1946, Serial No. 710,588

1 Claim. (Cl. 158—91)

1

This invention relates to new and useful improvements and structural refinements in oil burners and the principal object of the invention is to provide a device of the character herein described which may be conveniently and effectively employed for curing of tobacco.

A further object of the invention is to provide an oil burner which is simple in construction and efficient, dependable and economical in operation.

Another object of the invention is to provide an oil burner which will readily lend itself to economical manufacture and which may be easily disassembled for purposes of cleaning, inspection or repair.

An additional object of the invention is to provide an oil burner which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is an end view of the invention, taken in the direction of the arrow 1 in Figure 2;

Figure 2 is a cross sectional view, taken substantially in the plane of the line 2—2 in Figure 1;

Figure 3 is a cross sectional view, taken substantially in the plane of the line 3—3 of Figure 2;

Figure 4 is a cross sectional view, taken substantially in the plane of the line 4—4 in Figure 3, and

Figure 5 is an end view of a flame spreader plate used in the invention, the same being taken in the direction of the arrow 5 in Figure 4.

Like characters of reference are used to designate like parts in the specification and throughout the several views.

Referring now to the accompanying drawings in detail, the invention consists of an oilburner designated generally by the reference character 10, the same embodying in its construction a horizontally disposed, tubular enclosure 11 provided adjacent one end thereof with a circular fire wall 12.

The fire wall 12 is retained in position by a plurality of lugs or brackets 13 which are welded or otherwise secured to the fire wall and connected to the enclosure 11 by suitable bolts or rivets 14.

The wall 12 is also provided with a central air opening 15 and with a plurality of auxiliary air openings 16, as is best shown in Figures 1 and 3.

2

The mixing device designated generally by the reference character 17 consists of a horizontally disposed tubular member 18 secured at one end thereof to the fire wall 12 in register with the air opening 15. The interior of the member 18 thus provides an air passage and a horizontal sleeve 19 is also secured at one end thereof to the wall 12 in spaced relation with respect to the member 18, thus affording an annular mixing chamber 19'.

The sleeve 19 is provided with a screw threaded boss 20, this receiving a fuel inlet nozzle 21 which, in turn, is connected to a suitable fuel delivery pipe 22 equipped with a control valve 23.

15 It will be observed that the nozzle 21 is disposed in a substantially vertical position.

The outer surface of the member 18 is provided with a fuel receiving well 24 and with a plurality of fuel channels 25 which extend from this well to the free edge 26 of the member. The well 24 is disposed at the top of the member 18, directly below the nozzle 21.

20 A cone-shaped flame spreader plate and air deflector 27 is provided on the inner surface thereof with a plurality of equally spaced lugs 28, these in turn, being recessed as at 29 to engage the edge portion 26 of the member 18. It will be noted that the plate 27 is spaced from the member 18 as well as the sleeve 19 and a suitable bolt 30, equipped with a nut 31, is employed for mounting the plate in position.

25 The bolt 30 extends through a suitable aperture provided in a cross bar 32 which is secured in the member 18 adjacent the opening 15.

30 When the invention is placed in use, fuel will gravitate from the nozzle 21 into the well 24 and along the channels 25, and the initial supply of air in the chamber 19' will be sufficient to facilitate combustion as soon as the fuel is ignited. This combustion will take place in the chamber 19' and the flames will pass outwardly there-

35 from through the open end of the chamber, being effectively spread in lateral directions by the plate 27. As the initial supply of air in the chamber 19' is used, a fresh supply of air will be drawn through the member 18 and deflected by the plate 27 into the chamber, so as to sustain combustion.

40 In addition, fresh air will be admitted into the enclosure 11 through the auxiliary openings 16 to sustain the flames passing outwardly from the chamber 19'.

45 The plate 27 will effectively spread the flame and efficient distribution of heat throughout the cross section of the enclosure 11 will thus be facilitated.

50 It is believed that the advantages and use of

the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

In a mixing device for oil burners, the combination of a horizontally disposed tubular member defining an air passage having inner and outer ends, the outer surface of said member being provided at the top thereof with a fuel receiving well and with a plurality of fuel channels extending downwardly in opposite directions from said well to the outer end of said member, a horizontally disposed sleeve surrounding said member in spaced relation and coacting therewith to provide an annular mixing chamber having a closed inner end and an open outer end, said sleeve being provided at the top thereof with a

5 fuel inlet disposed above said well whereby fuel may gravitate from said inlet into the well and along the channels of said member, and a combined air deflecting and flame spreading plate mounted vertically adjacent the open end of said chamber whereby air travelling through said passage may enter the chamber to support combustion of fuel in said channels.

WAID C. PAIT.
